UNITED STATES PATENT OFFICE.

ROYAL D. TOMLINSON, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

CONDENSER.

1,085,182.

Specification of Letters Patent. Patented Jan. 27, 1914.

Application filed April 6, 1912. Serial No. 689,845.

To all whom it may concern:

Be it known that I, ROYAL D. TOMLINSON, a citizen of the United States, residing at Milwaukee, in the county of Milwaukee and 5 State of Wisconsin, have invented a certain new and useful Improvement in Condensers, of which the following is a specification.

This invention relates to a condenser for the steam of an engine, especially an engine 10 of the turbine class.

The object of the invention is to improve the construction of condensers, especially in the feature of forced injection of water thereto and the elimination of expensive 15 valves in the steam pipe to the condenser, and in the separation of the air taken from the condenser, from the water used in its extraction.

Another object is to provide a condenser 20 with two distinct water injection pipes, one natural and the other forced.

Another object of the invention is to have a single pump to supply the water used when the condenser is operated by forced injection and also to supply that used to eject 25 the air from the condenser.

In order to better make known this invention, reference is made to the accompanying drawing showing one embodiment 30 thereof, in which,

Figure 1 is a diagrammatic showing partly in section, of the condenser system. Fig. 2 is a similar showing viewed at right angles to the showing in Fig. 1. 35 Fig. 3 is a longitudinal section through the condenser. Fig. 4 is a transverse section through the condenser on the line IV—IV of Fig. 3. Fig. 5 is a sectional view through the guard plate applied to the 40 discharge pipe of the air ejector.

Referring to the drawing, especially Figs. 1 and 2 thereof, the primary devices of the condenser system are a steam turbine 1 delivering exhaust steam to a condenser 4, 45 from which the condense water passes to a centrifugal pump 19, and thence to a hot well 37. A second centrifugal pump 20 supplies water to the air ejector 16 and to the condenser 4. These two pumps 19, 20, are 50 driven from a common shaft by a motor 21, which may be either a steam turbine or an electric motor.

The piping connections will now be explained. The injection pipe 8 originates at 55 its lower end in cold well 24, passes up-

wardly along the side of the condenser 4, around to the end of the condenser 4 by a U-pipe 6 and connects to the condenser 4 at the lower part of the left end thereof as seen in Fig. 2. A main injection valve 7 60 is located in the U-pipe 6 and is operated by hand wheel 2. The exhaust pipe 3 from the turbine 1 connects to condenser 4 at the neck 25 at the top of the condenser. The discharge pipe 9 for injection water and condense water connects to the condenser 4 at the neck 35 at the bottom of the condenser, extends downwardly in a sort of S-shape and connects to the inlet of pump 19, the discharge pipe 18 of which extends into 70 the hot well 37. The check valve 17 is located in the discharge pipe 18. An air ejection pipe 5 connects to the condenser 4 at the upper portion of the left end thereof as seen in Fig. 2, and extends downwardly to its connection with the air ejector 16 discharging to well 22, which is in communication with cold well 24 as more clearly disclosed in Fig. 2. A valve 12 is interposed in the air ejection pipe. The pump 20 has 80 its suction pipe 23 originating in the cold well 24 and its discharge pipe 14 is divided into two branch pipes 11, 15, the former of which extends upwardly and connects with the U-pipe 6 between the main injection valve 7 and the condenser 4 (or it may connect directly to the condenser 4), and the latter of which extends downwardly and connects to the air ejector 16. A valve 10 is interposed in the branch pipe 11, and a valve 151 in the branch pipe 15. A steam primer 13, 13, is connected to the discharge pipe 14 of the pump 20 and preferably discharges into the branch pipe 15. 85

Referring to Figs. 3 and 4 of the drawing, the condenser structure will now be described. The water box 32 is connected to the U-pipe 6 supplying the main injection water, and from this water box 32 extend a series of wedge shaped troughs 28 into the 90 main body of the condenser. These troughs 28 have serrated edges and are supported at their right ends as seen in Fig. 3, by lugs 29 on the end plate 290 for the right end of the condenser. These troughs have baffle plates 26 supported directly thereover. Underneath the troughs and alternating therewith, are splash plates 33 supported longitudinally from end to end of the condenser 105 on lugs provided for that purpose. These 110

splash plates have their upper surfaces indented. The discharge neck 35 at the lower part of the condenser is extended therein a short distance and has its upper edge 34 5 serrated. An air pocket 30 is formed above the water box 32 and connects to the air ejection pipe 5. A guard plate 27 separates the steam and air spaces of the upper part of the condenser. Convenient hand holes 36 10 may be provided in the end plate 290.

Referring to Fig. 5, a guard plate or spreader 38 is connected to the discharge end of the air ejector 16 or the pipe extending therefrom, by means of connecting 15 posts 39. The middle portion of the guard plate or spreader 38 is made in the shape of a cone.

The operation of the condenser is as follows: In order to begin operations it is necessary to prime the centrifugal pump 20; the other pump 19 need not be primed because it receives its supply by gravity. Steam is admitted to the primer 13, which at its right hand connection, as seen in Fig. 2, constitutes an ejector, and at its left hand merely constitutes a discharge connection for the mixture of steam and the water ejected to conduct same to the well 22 through the air ejector 16. In order to have the primer operate it is necessary to shut off valve 10 in the forced injection pipe 11 and valve 151 in the water pipe 14 supplying the air ejector 16. Main valve 7 and air valve 12 are assumed to have been closed. 25 The pump 20 having been thus primed, valve 10 is then opened to admit the forced injection water to the condenser 4 through the pipe 11. The main injection valve 7 is then partially opened, say one-third, so that 30 the injection water passes to the condenser 4 in two ways; first the forced injection through the pipe 11, and second, the natural injection by atmospheric pressure through the injection pipe 8 and U-pipe 6. This 35 natural injection of water through pipe 8 is brought about by the establishment in the condenser 4 of a vacuum on account of the admission of the forced injection water. Under these conditions the water and air 40 are removed from the condenser through the discharge pipe 9 by the main pump 19 and discharge pipe 18 to the hot well. Valve 151 is now opened and valve 10 is closed, thus diverting the forced injection water 45 from the condenser to the air ejector 16. The main injection valve 7 is now opened to the extent required for normal operation, and lastly the valve 12 in the air ejection pipe 5 is opened. 50 In case the vacuum should be lost by reason of the loss of the flow into the condenser of the main injection water by atmospheric pressure because of low water in the cold well 24, the water in said well will at 55 the same time drop below the inlets of the

main injection pipe 8 and the suction pipe 23 of the pump 20. This will put the pump 20 out of commission so that no water will be pumped thereby to the air ejector 16. In case the vacuum is lost because the pumps 70 stop by reason of failure of the motor which drives them, then water will cease to flow to the air ejector 16 and the vacuum will be lost by air entering through the air ejector and the air ejector pipe 5. This will 75 also stop the inflow of injection water through the main injection pipe 8. In either of these cases of loss of vacuum all the valves should be closed and the system started as first described.

In case the vacuum should become reduced due to overload and consequently the main injection water supply level should drop to a point where the inflow is almost or entirely cut off by reason of the water 85 not rising high enough in the main injection pipe 8 to flow into the condenser, the valve 12 in the air ejection pipe 5 should be closed and the valve 10 in the forced injection pipe 11 opened followed quickly by 90 the closing of the valve 151 supplying water to the ejector 16. If these changes are accomplished reasonably quick enough the vacuum may be recovered without being entirely lost. It will be seen that this forced 95 injection water pipe 11 provides a means for positively getting water into the condenser 4 irrespective of the vacuum pressure. The turbine may be carrying full load and it is unnecessary to shut off the steam entering 100 the condenser. It may be necessary in making these changes to recover the vacuum that the main injection valve 7 be partially closed to prevent the forced injection water from passing back into the main injection 105 water pipe 8 instead of passing to the condenser 4.

In some cases where the water supply is limited it might be advantageous to discharge the water used for operating the air 110 ejector 16 back into the cold well 24 through its communication with well 22. In order to do this without passing the entrained air back to the cold well 24, a device is attached to the discharge pipe of the air ejector 16 115 which separates out the air entrained in the water before or at the time the water passes into the well 22. This device is shown in section in Fig. 5.

The device for separating the air from the 120 water operates by diverting the water discharged from the air ejector along the spreader 38 in a direction along and substantially at the surface of the water in the well 22. The upper surface of the spreader 125 38 is substantially at the water level of the well. By this means the entrained air is liberated from the water and passes to the atmosphere and the water mingles with that in the well. The saving of water effected is 130

that all the water used to operate the air ejector 16 is passed back into the well 24 through its communication with the well 22, as already stated.

5 It should be understood that it is not desired to be limited to the exact details of construction shown and described, for obvious modifications will occur to a person skilled in the art.

10 It is claimed and desired to secure by Letters Patent,—

1. In combination, a condenser, a water-actuated air ejector connected thereto, a pipe for supplying actuating water to said ejector, 15 a second pipe for injection of water to said condenser, and a pump common to said air ejector and injection pipes.

2. In combination, a condenser, a main water injection pipe, a main water ejection pipe, a pump in said latter pipe, an air ejection pipe, a water-actuated air ejector in said pipe, a secondary injection pipe, and a second pump connected to said secondary pipe and to said ejector.

25 3. The combination with a condenser, of a water injection pipe and an air ejection pipe connected thereto, valves in said pipes, an air ejector to which said ejection pipe leads, a pump, pipe connections from said pump to said ejector and to said injection pipe on the condenser side of its valve, and valves in said connections.

4. In combination, a condenser, a water-actuated air ejector connected thereto, a main 35 pipe for injection of water to said condenser, a second pipe for injection of water to said condenser, means permitting alternative use of either pipe, and a pump connected to one of said pipes and to said ejector.

40 5. In combination, a condenser, hydraulic means for withdrawing air therefrom, an air and water discharge pipe for said means, a well for the discharge from said pipe, said well being open to atmosphere, and a

45 spreader for said discharge having its upper surface substantially at the surface of the water in said well.

6. In combination, a condenser, hydraulic means for withdrawing air therefrom, a well, a pipe conveying a mixture of water 50 and air from said hydraulic means to said well, and a spreader spaced below the end of said pipe and located in the path of the water and air from said pipe, the lower end of said pipe being open to atmosphere. 55

7. In combination, a condenser, hydraulic means for withdrawing air therefrom, a well, means for conveying a mixture of water and air to said well from said hydraulic means, and a spreader having its 60 upper surface substantially at the surface of the water in said well onto which said mixture is discharged, the lower end of said mixture conveying means being open to atmosphere. 65

8. In combination, a condenser, hydraulic means for withdrawing air therefrom, a well, means for conveying a mixture of water and air to said well from said hydraulic means, and means for delivering said 70 mixture along the surface of water in said well.

9. In combination, a condenser, a well, a pipe for injecting water from said well to said condenser, an air ejector communicating 75 with said condenser and discharging into said well, and a pump taking water from said well and discharging it into said air ejector.

10. In combination, a condenser, a well, a 80 pipe for injecting water from said well to said condenser, an air ejector communicating with said condenser and discharging into said well, a pump taking water from said well and discharging it into said air ejector, 85 and a spreader in said well to receive the discharge from said air ejector.

In testimony whereof, the signature of the inventor is affixed hereto in the presence of two witnesses.
